Law, PLLC

CLAIM

The ornamental design for a vehicle front driver seat, as
shown and described.

DESCRIPTION

FIG. 1 is a top front right perspective view of a vehicle front
driver seat;

FIG. 2 is a bottom front right perspective view of the vehicle
front driver seat;

FIG. 3 is a top rear right perspective view of the vehicle front
driver seat;

FIG. 4 is a front elevational view of the vehicle front driver
seat;

FIG. 5 is a rear elevational view of the vehicle front driver
seat;

FIG. 6 is a right side elevational view of the vehicle front
driver seat;

FIG. 7 is a left side elevational view of the vehicle front
driver seat; and,

FIG. 8 is a top plan view of the vehicle front driver seat.
The broken lines define the bounds of the claim. The broken
lines and the lightened portions of the article shown inside
the broken lines form no part of the claimed design.

1 Claim, 8 Drawing Sheets
